SPICE RACK

James Edward Stewart, 31 Ravensbourne Crescent,
Islington, Ontario, Canada

Filed Aug. 7, 1969, Ser. No. 18,579

Term of patent 14 years

Int. Cl. D6—99

U.S. Cl. D33—3

FIG. 1 is a front elevational view of a spice rack showing my new design;

FIG. 2 is a sectional view on line 2—2 of FIG. 1; and

FIG. 3 is a top plan view.

I claim:

The ornamental design for a spice rack, as shown.
